UNITED STATES PATENT OFFICE.

SURN JACKSON, OF STOCKTON, CALIFORNIA.

MEANS FOR ADMINISTERING AIR OR GAS.

No. 920,955.

Specification of Letters Patent.

Patented May 11, 1909.

Application filed August 17, 1908. Serial No. 448,808.

To all whom it may concern:

Be it known that I, SURN JACKSON, a citizen of the United States, residing at Stockton, in the county of San Joaquin, State of California, have invented certain new and useful Improvements in Means for Administering Air or Gas; and I do declare the following to be a full, clear, and exact description of the same, such as will enable others skilled in the art to which it appertains to make and use the same, reference being had to the accompanying drawings, and to the characters of reference marked thereon, which form a part of this application.

15 This invention relates to improvements in medical apparatus and particularly to a means for administering medicated gas or air to the stomach for treatment of dyspepsia, sour stomach, bowel troubles and similar 20 complaints, the main medicament used being natural or water gas which contains salt, soda, iron, sulfur and magnesia, all of which elements are helpful for the disorders enumerated.

25 The object of the invention is to produce a means for administering the gas or air in such a manner as to permit it to be taken into the stomach in such quantities as may be desired in such a manner as to admit it 30 easily and without distress to the patient.

Also to produce a simple and inexpensive device for the purpose. These objects I accomplish by means of a tube having a mouth piece, a cock regulated gas or air inlet there- 35 to, a liquid inlet into said tube having a lift valve therein, and an air pump for drawing liquid and gas into said tube and discharging it through said mouth piece whereby the liquid will be gasified or aerated as it is taken 40 into the stomach; also by such other and further construction and relative arrangement of parts as will more fully appear by a perusal of the following specification and claim.

45 In the drawings similar characters of reference indicate corresponding parts in the several views.

Figure 1 is a side elevation of the complete device. Fig. 2 is a vertical section of the 50 device. Fig. 3 is a side elevation of a gas storage tank.

Referring now more particularly to the characters of reference on the drawings I des-

ignates a standard having a projecting support 2 maintaining a tube 3 having a removable mouth piece 4, said tube being connected with a gas or air inlet tube 5 having a regulating cock 6. If gas is to be used a flexible tube 7 may be connected with a jet 8 or with a storage tank 9 (Fig. 3). The lower end of the tube 3 is provided with a lift valve 10 while 11 is an air suction pump connected with said tube 3 intermediate said valve 10 and tube 5.

To use the appliance the operator immerses the valve 10 in any desired liquid such as water, coffee, tea, milk or other desired drink and then inserts the mouth piece 4 into the mouth and operates the pump 11. With the upward motion of the pump 11 it draws into the tube 3 a quantity of this liquid through the valve 10 and a quantity of the gas or air through the tube 5. Then with the downward motion of such pump 11 it mixes the liquid and gas or air together and they are discharged through the mouth piece 4 into the mouth of the operator and thence swallowed into the stomach.

The mouth piece may be removable as shown by 4^a hence one appliance may be used for several people without fear of contagion.

For sterilizing the appliance I have provided a funnel 12 which may be screwed into the bottom of the valve 10 and then the appliance would be inverted and filled through said funnel with any desired sterilizing element such as hot water or similar sterilizer.

The tank 9 may be portable for supplying the air or gas to any person or persons desiring it.

The cock 6 is used to control the amount of gas or air admitted to the tube 3.

From the foregoing description it will be readily seen that I have produced such an appliance as substantially fulfills the objects of the invention as set forth herein.

While this specification sets forth in detail the present and preferred construction of my invention still in practice, such deviations from such detail may be resorted to as do not form a departure from the spirit of the invention.

Having thus described my invention what

I claim as new and useful and desire to secure by Letters Patent is:—

A tube, a removable mouth piece thereon, a lift valve in said tube, a gas inlet in said tube, a pump connected with said tube and a removable funnel disposed in said lift valve, as set forth.

In testimony whereof I affix my signature in presence of two witnesses.

SURN JACKSON.
